UNITED STATES PATENT OFFICE.

ROBERT T. EVANS AND WALTER G. NORD, OF YOUNGSTOWN, OHIO.

STEAM-TRAP.

1,117,359.

Specification of Letters Patent. Patented Nov. 17, 1914.

Application filed June 8, 1911. Serial No. 631,923.

To all whom it may concern:

Be it known that we, ROBERT T. EVANS and WALTER G. NORD, citizens of the United States, and residents of Youngstown, county 5 of Mahoning, and State of Ohio, have jointly invented a new and useful Improvement in Steam-Traps, of which the following is a specification, the principle of the invention being herein explained and the 10 best mode in which we have contemplated applying that principle, so as to distinguish it from other inventions.

Our invention relates in general to an improved steam trap and in particular to the 15 valve mechanism for discharging the contents of the trap.

The object of the invention is to provide a discharge valve that will be simple and durable, and permit of a more rapid discharge than in prevailing types of construction.

Our trap comprises a drain-chamber adapted to collect the water condensed out 25 of the steam in passage in a line and valve mechanism for periodically discharging the water from the drain chamber.

To the accomplishment of this and related ends, said invention consists of the means hereinafter fully described and particularly pointed out in the claim.

The annexed drawings and the following description set forth in detail certain mechanism embodying the invention, such disclosed means constituting, however, but one 35 of various mechanical forms in which the principle of the invention may be used.

In said annexed drawings: Figure 1 is a vertical section through the steam trap, showing the valve mechanism; Fig. 2 is a 40 vertical section on the line 2—2, Fig. 1.

In Fig. 1 the drain-chamber 1 is designed to be connected with a steam line (not shown) by the pipe 2, and has a drain pipe 3 which is normally kept closed by suitable 45 means (not shown). The drain-chamber 1 is also provided with an air valve 4 normally kept closed and an outlet-pipe 5 normally kept closed by valve mechanism to be described hereafter. The said valve 50 mechanism comprises a ball valve 6 normally retained on its seat 7 by gravity, thus closing the discharge pipe. At one side of the valve-seat 7 is an inclined runway 8, up which the ball is adapted to be moved 55 by the reciprocable plunger 9 attached at one end to the short arm of the bell-crank

lever 10 which is oscillatorily mounted on the pin 11 and is pivotally connected to the bucket-float 12 by the bolt 13. The ball valve 6 operates in a supplementary casing 60 or chamber 20 attached to the side of the main chamber 1 about the outlet 5. Integral with the casing 20 is a lug 21 to which is pivotally attached the bell crank lever 10 by the pin 11. The plunger 9 is a reciprocable in the slot 14 into which it fits tightly and is provided with a beveled collar 15 adapted to engage the seat 16 on the side wall around the slot 14. The siphon-pipe 17 enters the inner chamber 18 above 70 the valve 6 and extends to the bottom of the bucket float in the normal floating position of the latter.

The operation of our trap is simple. The water enters by the pipe 2 and is directed 75 vertically downward by the baffle 19 which prevents the water from passing directly into the bucket. As the water rises it floats the bucket until the bottom of the latter is in contact with the end of the siphon 80 pipe when the bucket is at its highest possible position as shown in Fig. 1. This action draws the plunger away from contact with the ball which then seats securely closing the discharge pipe. As the water rises 85 over the top of the bucket, the latter is filled and finally sinks to the bottom rotating the bell-crank lever and thus causing the plunger to move the ball up the inclined runway, opening the valve. The water is 90 then forced out through the pipe 17 by the pressure of the steam. When emptied of water the bucket is floated by the remaining water in the chamber and the operation is repeated.

The advantages which we claim for our valve are the simplicity of construction and operation and the increased life of the valve by reason of the ball being slightly rotated by the discharging water, causing it to seat 95 on a different portion of the circumference each time, thus practically "grinding in" the valve continually. By using a plunger which is transversely disposed with respect to the valve we do not diminish the area of 100 the valve opening in the least, thus securing that rapid discharge which is essential to a good steam trap.

We do not of course limit the use of this valve mechanism, which is in itself new as 110 well as in combination with a liquid drain chamber, to the use here shown, but may

adapt it to various fluid-handling mechanisms.

Other modes of applying the principle of our invention may be employed instead of the one explained, change being made as regards the mechanism herein disclosed, provided the means stated by the following claim or the equivalent of such stated means be employed.

10 We therefore particularly point out and distinctly claim as our invention:—

In a mechanism of the class described, the combination with a liquid drain chamber provided with a removable cover and 15 having inlet and outlet openings; of a second and smaller chamber removably attached within said drain chamber about such discharge opening and adjacent to said cover; valve mechanism disposed within 20 said second chamber and adapted to control such discharge opening, said valve

mechanism comprising a movable ball and seat therefor; a runway mounted in said second chamber adjacent said valve seat and inclined toward the same; said second chamber having inlet and discharge openings; a pipe attached to such inlet opening in said second chamber and extending outward and downward in said first-named chamber; a lever pivotally mounted upon 30 said second chamber and adapted to actuate said ball valve; and an open bucket float attached to lever and actuated by the liquid level in said first-named chamber, said pipe extending within said bucket.

35 Signed by us, this 6th day of May, 1911.

ROBERT T. EVANS.
WALTER G. NORD.
